UNITED STATES PATENT OFFICE.

WILLIAM H. WILDER, OF WASHINGTON, DISTRICT OF COLUMBIA.

DESIGN FOR PLOW-BEAMS.

Specification forming part of Design No. 7,688, dated August 18, 1874; application filed July 16, 1874.
[Term of Patent 14 years.]

To all whom it may concern:

Be it known that I, WILLIAM H. WILDER, of Washington, District of Columbia, have invented an Improvement in Designs for Plow-Beams, of which the following is a specification:

During many years, experience in the manufacture and sale of cast-iron plows, I have often observed that the finish and general appearance of a plow would make a great difference in regard to the sale, and also apparently to the satisfaction which the plow would permanently give to the purchaser. Plow-manufacturers generally understand this, and they often imitate the general appearance of a plow which has already acquired a good reputation. This experience has led me to invent an appropriate and simple design for casting the plow-beams with flutes and ribs upon the sides.

In the accompanying drawings, Figure 1 represents the left-hand side of a plow-beam with my design molded thereon. Fig. 2 represents the right-hand side of the beam with my design thereon.

I propose to apply my design to that class

of plows in which the beam and standard are both cast in one piece, and yet it may be applied to other plows, if desired; and it consists in a series of flutes and ribs cast upon the sides of a plow-beam, as shown in the drawings. Between the two thick edges usually cast in the beam for strength, it is usual to cast the surface or sides of the beam flat. This usual flat surface I have ornamented with ribs and flutes, or a transversely-corrugated surface, as seen at A, Figs. 1 and 2. This ornamentation requires no finishing, and as the ribs and flutes run longitudinally and make the same general curves as the whole beam, the plow-beam has a very pleasing and attractive appearance.

Having fully described my invention, I claim—

As an ornamental design for the sides of plow-beams, the series of flutes and ribs, substantially as shown and described.

WILLIAM H. WILDER.
